UNITED STATES PATENT OFFICE.

HARRY ROZENSKE, OF DETROIT, MICHIGAN.

DESIGN FOR A PINCER.

55,487.

Specification for Design.

Patented June 15, 1920.

Application filed October 11, 1919. Serial No. 330,154. Term of patent 7 years.

To all whom it may concern:

Be it known that I, HARRY ROZENSKE, a citizen of Poland, residing at Detroit, in the county of Wayne and State of Michigan, have invented a new, original, and ornamental Design for a Pincer, of which the following is a specification, reference being had to the accompanying drawing, forming part thereof.

The figure is a view in perspective of a pair of pincers, showing my new design.

I claim:

The ornamental design for a pincer, as shown.

HARRY ROZENSKE.
